[57] ABSTRACT

A passive sonar array mounting and recovery apparatus comprising a frame that is mounted on a plurality of legs. A net is stretched across the interior region of the frame and is held in place with twine. Centrally located and extending vertically upward from the frame is a center post. A plurality of grapnel rods have their ends attached to the upper end of the center post and the other ends attached to the periphery of the frame. The grapnel rods are uniformly spaced apart and extended outward and downwardly from the top of the center post to the frame. At the corners of the frame are vertically extending transducer support members. Two transducers are respectively supported by a horizontal tower and a vertical tower that are attached to and extend outwardly from the frame.

PASSIVE SONAR ARRAY MOUNTING AND RECOVERY APPARATUS

BACKGROUND OF THE INVENTION

1. Field of the Invention

The present invention relates to an apparatus that may be recovered by grappling techniques and more particularly to a passive sonar array mounting and recovery apparatus that may be safely and readily retrieved from the ocean floor by grapnel dragging techniques.

2. Description of Prior Art

In retrieval of underwater apparatus two primary types of systems have been in use. One is an active recovery system in which an element of the underwater apparatus is separated from the apparatus and floats to the surface. The other is a passive recovery system in which the apparatus is recovered by grapnel dragging of some kind.

The feature of most passive systems which makes them difficult or relatively inefficient is the direction of travel required of the towed recovery element or grapnel. This direction is horizontal, whether dragging along the bottom, attempting to snare within a towed loop, or inserting a hook device in a vertical eye of the unit. Because the towed element is at the end of a long, flexible (but inextensible) cable, horizontal control is exercised through the high compliance of the horizontal flexibility of the cable. Vertical motion of the cable, by contrast, is characterized by a high degree of stiffness in the vertical direction, so that vertical control is firm, whereas horizontal control is soft.

This feature, good vertical control, is exploited in the passive recovery apparatus of the present invention. The target to be captured is made large in the horizontal direction so that vertical motion can be used to pierce the target with the recovery grapnel.

SUMMARY OF THE INVENTION

Briefly, the passive sonar array mounting and recovery apparatus of the present invention comprises a frame that is mounted on a plurality of legs. A net is stretched across the interior region of the frame and is held in place with twine. Centrally located and extending vertically upward from the frame is a center post. A plurality of grapnel rods have their ends attached to the upper end of the center post and the other ends attached to the periphery of the frame. The grapnel rods are spaced apart and extend outward and downwardly from the top of the center post to the frame. At the corners of the frame are vertically extending transducer support members. Two transducers are respectively supported by a horizontal tower and a vertical tower that are attached to and extend outwardly from the frame. In practice, the recovery head or grapnel is maneuvered over the recovery apparatus and then dropped through it quickly. The grapnel is then pulled upward where it is snared by the net. The twine is weaker than the net and releases thereby moving the grapnel horizontally and into contact with the grapnel rods. The upward pull on the recovery cable then causes the grapnel to follow upwardly and inwardly along a grapnel rod until it becomes snared by a plurality of grapnel rods adjacent the upper end of the center post. The apparatus is then pulled upward, remaining stable because the upward pull is through its center of gravity.

STATEMENT OF THE OBJECTS OF INVENTION

An object of the present invention is to provide an apparatus that is suitable for mounting sonar transducers and provides for easy and safe recovery by grapnel dragging.

Another object is to provide a passive sonar array mounting and recovery apparatus that may be placed in ocean water for several years and be operative and easily removed.

Other objects, advantages and novel features of the invention will become apparent from the following detailed description of the invention when considered in conjunction with the accompanying drawings wherein:

BRIEF DESCRIPTION OF THE DRAWINGS

FIG. 1A is a schematic diagram of a recovery ship dropping a grapnel into the passive sonar array mounting and recovery apparatus of the present invention;

FIG. 1B is a pictorial view of the passive sonar array mounting and recovery apparatus of the present invention;

FIG. 2 is a schematic diagram of the center post of the apparatus of FIG. 1B;

FIGS. 3A and 3B are schematic diagrams of the upper section of the center post of FIG. 2; and

FIGS. 4A, 4B, and 4C are schematic diagrams of the legs of the apparatus of FIG. 1B.

The passive sonar array mounting and recovery apparatus 11 of the present invention is generally shown in FIG. 1A, and more specifically, shown in FIG. 1B. The mounting and recovery apparatus 11 is lowered to the ocean floor and will normally remain there for as long as ten years. The apparatus includes a plurality of passive sonar transducers which form a three dimensional underwater sonar receiver array for tracking subsurface or surface objects that emit noise. The signals received by the sonar receivers may be transmitted several miles to a shore station through an electrical cable that lies on the ocean floor. After the apparatus has been on the ocean floor for a period of time, it may be necessary to recover it for maintenance, modification, or removal. To recover the apparatus the general location is first determined by any of several techniques such as prior mapping or sonar detection by the recovery vessel. After the general location is established, a hook or grapnel is lowered in the general vicinity of the apparatus and firmly attaches itself thereto so that the apparatus is recovered quickly and with no damage.

In FIG. 1A is illustrated an ocean vessel 5 lowering a grapnel 7 by means of a cable 9 for recovering from the ocean floor 12 the passive sonar array mounting and recovery apparatus 11 of the present invention.

In FIG. 1B is illustrated the details of apparatus 11 of the present invention. It is to be understood that the apparatus of the present invention is not limited to use with sonar, but may be used for any purpose where easy and safe recovery is desired. When used with a sonar system, the present invention may have overall dimensions of about 30 feet wide by 50 feet high. The principal purpose of this recovery apparatus is to provide a structure that is effective for mounting a passive sonar system and may be effectively retrieved by grapnel dragging.

The principal elements of apparatus 11 of FIG. 1B include array frame 13, horizontal tower 15, upright tower 17, legs 19, 21 and 23, center post 25, nets 27

and 29, transducer support members 31, 33 and 35, sound transducers 37, 39, 41, 43 and 45 and a plurality of grapnel wires or rods 47. The twine 57 is selected to be weaker than the netting so that it will pull loose from one of the sides when the grapnel is lifting the net

Array frame 13 has an equilateral triangular exterior configuration and includes structural members 49, 51 and 53 which are connected at their ends by welding, riveting, or the like. Cross member 55 is connected to the interconnection point of members 49 and 51 to the center point of member 53. Nets 27 and 29 are attached to the right triangular areas formed between cross member 55 and members 49, 51 and 53. Nets 27 and 29 are preferably made of nylon or other equivalent material that will not deteriorate upon being submerged in ocean water for a period of approximately ten years. The nets are attached to the frame by nylon twine 57. THE TWINE %& IS SELECTED TO BE WEAKER THAN THE NETTING SO THAT IT WILL PULL LOOSE FROM ONE OF THE SIDES WHEN THE GRAPNEL IS LIFTING THE NET. This breaking loose of the twine will cause the grapnel to move laterally and into contact with one of the rods 47. However, the twine is selected to be of sufficient strength to hold the net in place and not release until the grapnel hook is above the plane of frame 13 and will therefore not hook into the array frame.

The lower end of center post 25 is attached to cross member 55 and is positioned at about the center of gravity of the apparatus which is about one-third of the length of cross member 55 measured from member 53. Attached to plates 59, 61 and 63, at the corners of frame 13, are transducer support members 31, 33 and 35 which may be made of 4-inch steel pipe and have a length of about 10 feet. Each of these support members is supported by a pair of braces 65 that interconnect the support members and the frame.

Each of towers 15 and 17 is made up of a plurality of steel rods 67 and adjustable tension rods 69. The two lower rods 67 of both towers are attached to structural member 53 and the upper rods 67 of both towers are attached to the base of center post 25. It should be noted that the free end of horizontal tower 15 is raised from the horizontal by a distance of about ten feet so that the transducer 43, attached to the end thereof, is in the same plane as transducers 37, 39 and 41. Also, the length of tower 15 is selected so that the distance of transducer 43 from each of transducers 37 and 41 is the same and all four of the transducers 37, 39, 41, and 43 form a square having a distance between each transducer of about 30 feet. The length of upright tower 17 is selected so that transducer 45 is about thirty feet directly above transducer 43.

Each of transducers 37, 39, 41, 43 and 45 is a receiver transducer including a preamplifier. Power is supplied to and information is received from each of the transducers by means of electrical cable 71 which may extend along the ocean floor to a shore station. Cable 71 passes through a conduit 73 having a flared end 75 and extends along the frame and towers to the various transducers.

Referring to FIGS. 1B, 4A, 4B, and 4C are illustrated legs 19, 21, and 23 which are attached to the respective corners of frame 13. Each leg is supported by a pair of braces 77 which are connected between the legs and the frame. As best depicted in FIGS. 4A, 4B and 4C, each of legs 19, 21 and 23, which may be 8-inch steel

pipe, includes a foot plate 79 that is about thirty inches square. Welded to the bottom of each leg is ring 81. Welded to each leg, about from four to six inches above ring 81, are three wedges 83 at about 120° intervals. 5 Plate 79 has an opening somewhat larger than the diameter of each leg. As illustrated in FIG. 4C, this leg configuration allows for stable footing on uneven ocean terrain because plate 79 can tilt to accommodate the uneven terrain. It should be noted that weight may be 10 added to the hollow portion of leg 21 to compensate for the weight of towers 15 and 17.

In FIGS. 2, 3A and 3B are shown the details of center post 25 of the system shown in FIG. 1B. Center post 25 may be made of 8-inch steel pipe having an upper section 85 and a lower section 87. Welded to the lower interior region of upper section 85 is disc 87 having a centrally positioned opening 89. The shank 90 of bolt 91 passes through this opening. Positioned below disc 87 and surrounding shank 90 are a plurality of circular fiber washers 93. These washers rest on disc 95 which is retained in position by nut 97 which is welded to shank 90 and to disc 95. Bolt 91 includes a shoulder 99 that rests on the periphery of the opening of disc 87 when it is free to move downwards. However, when pulled upwards as shown in FIG. 2, there is a space between shoulder 99 and the upper surface of disc 87. This space provides for release of fiber washers 93 when the apparatus initially comes to rest on the ocean floor. Attached to the eye of bolt 91 is one end of shackle 101 and attached to the other end of shackle 101 is chain 103. Attached to the upper end of chain 103 is shackle 105 and attached to shackle 103 is ring 107. A lowering hook 109, which may or may not be a grapnel, is connected to ring 107 for lowering, by means of cable 111, apparatus 11 into the ocean. When the apparatus comes to rest on the bottom, the hook becomes disengaged and is raised back to the vessel.

Fiber washers 93 function as a clutch. That is, when the apparatus 11 is initially lowered into the ocean, the apparatus may rotate and severely twist lowering cable 111. Upon coming to rest on the ocean floor the fiber washers provide a clutch action that permits the cable to unwind slowly. This eliminates rapid unwinding of the cable which could cause the lowering hook to get caught in the center post or grapnel rods. It also prevents damage to the center post and the grapnel rods which could be caused by rapid spinning of the various rotatable parts of the center post.

On the bottom end of upper section 83 is welded exterior flange 113 and on the upper end of lower section 85 is welded exterior flange 115. Flanges 113 and 115 are held together by a plurality of bolts 117. Welded to the outside surface of upper section 83, above flange 113, is ring 119. Welded to ring 119 are a plurality of grapnel rods 47. Each grapnel rod 47 consists of arm 121 and extension 123. The lower part of arm 121 is shaped to fit tightly against ring 119 and the outside surface of upper section 83 and extends upwards at an approximately 60° angle from the horizontal. The upper end of arm 121 turns outwards at an approximately 90° angle. The end of arm 121 is provided with female threads that accommodate the male threads of extension 123. Forming the grapnel rods into these two parts provides for ease of shipment and adjustability prior to bolting the extensions 123 to the frame 13. Gussets 125 are used to provide additional support for arms 121 and, as best depicted in FIG. 3A and 3B, a

plurality of grapnel deflector plates 127 are welded between adjacent arms 121 to prevent the grapnel from getting caught in the closely spaced regions of adjacent arms.

What is claimed is:

1. A mounting and recovery apparatus comprising:
  - a. a frame;
  - b. a post having one end attached to the frame and inside the periphery of said frame;
  - c. said post extending vertically from the plane of said frame;
  - d. means for connecting at least one net to said frame;
  - e. a plurality of rods interconnecting the free end of said post and the periphery of said frame; and
  - f. said means releases at least a part of said net from said frame when a predetermined force is applied to said net.
2. The apparatus of claim 1 wherein:
  - a. said means comprises twine; and
  - b. said twine has lesser strength than said at least one net.
3. The apparatus of claim 2 wherein:
  - a. said at least one net and twine are made of plastic material.
4. The apparatus of claim 1 including:
  - a. means for supporting a plurality of sound transducers.
5. The apparatus of claim 4 wherein:
  - a. said means includes a plurality of support members and first and second towers;
  - b. said support members being attached to the periphery of said frame and extending vertically to the plane of said frame;
  - c. said first tower being connected to said frame and extending outwardly from the periphery of said frame and upwardly from the plane of said frame;

and

d. said second tower being connected to said frame and extending outwardly from the periphery of said frame and upwardly from the plane of said frame and from said first tower.

6. The apparatus of claim 1 wherein:
  - a. the periphery of said frame has three sides forming a triangle;
  - b. said frame includes a cross member interconnecting one corner of said frame and the center position of the opposite side of said frame; and
  - c. said post being connected to said cross member.
7. The apparatus of claim 6 wherein:
  - a. said post is connected to said cross member at about the center of gravity of said apparatus.
8. The apparatus of claim 7 wherein:
  - a. said at least one net comprises first and second nets;
  - b. said first net being connected between said cross member and all of a first side and half of a second side of said frame; and
  - c. said second net is connected between said cross member and all of a third side and the other half of said second side of said frame.
9. The apparatus of claim 1 wherein:
  - a. said center post is a hollow cylinder;
  - b. support means extending through said cylinder;
  - c. a member connected to said cylinder;
  - d. one end of said support means releasably connected to said member; and
  - e. clutch means for slowly releasing said support means from said member.
10. The apparatus of claim 1 including:
  - a. a plurality of legs extending from said frame in a direction opposite to the direction of said post.
